UNITED STATES PATENT OFFICE.

WRAY FALWELL, OF BOSTON, MASSACHUSETTS, ASSIGNOR OF ONE-HALF TO CHARLES H. TRAISER, OF BOSTON, MASSACHUSETTS.

SPARK-PLUG.

981,752.

Specification of Letters Patent. Patented Jan. 17, 1911.

Application filed January 24, 1910. Serial No. 539,690.

To all whom it may concern:

Be it known that I, WRAY FALWELL, a citizen of the United States, residing at Boston, in the county of Suffolk and State of Massachusetts, have invented certain new and useful Improvements in Spark-Plugs, of which the following is a specification.

My invention relates to removable spark-plugs for internal combustion engines, and its objects are to provide a better means of insulation between the electrodes, to permit greater freedom of movement of the grounded electrode without removing it from the devices holding the same, to employ 10 spring actuated means in locking the grounded electrode to said holding devices, to completely obstruct the escape of the combustion gases, to better secure and protect the insulation, to prevent the over heating 20 of the plug, and to simplify and render more effective the operation of the several parts.

My invention consists of a spark plug having a grounded shell-electrode and an electrode stem located within the same and effectually insulated therefrom, a holder having a recess for receiving and holding said shell-electrode, an open resilient ring resting upon an inclined seat formed at the 30 bottom of said recess, the shell-electrode having an annular projection shaped to come in close contact with said seat and normally engaging the same below said ring, and a lock-nut threaded to engage the top of said 35 holder, the lower end of said lock-nut extending downwardly into said recess and forcing the ring into close contact with the upper face of said projection.

My invention further consists in 40 structuring the handling cap of greater longitudinal dimensions than heretofore and in providing air spaces between the wall of said cap and the adjacent surface of the plug.

My invention further consists in 45 structuring the insulation sleeve with an enlargement thereon, which enlargement is confined in a recess formed within the grounded electrode shell and secured to the same by a collar, the other portions of the 50 said sleeve having air spaces between the same and the grounded electrode.

My invention further consists in other 55 improvements and modifications more particularly pointed out and claimed in the following specification.

I attain the several objects above set forth by the construction illustrated in the accompanying drawing, in which similar numerals of designation refer to similar parts throughout the several views.

Figure 1. is a side elevation of my improved spark plug and holder therefor; Fig. 2. is a vertical section of the same; Fig. 3. is an enlargement of the lower portion of Fig. 2, showing the spark-plug removed, and the 60 position assumed by the locking ring when the lock-nut is released; Fig. 4. is a view of the locking ring; Fig. 5. is a vertical section showing a modification of the lock-nut, the lower end of which is shown split into downwardly extending arms; Fig. 6. is a view of the lock-nut shown in Fig. 5 looking from below. Fig. 7 is a vertical section of the holder and adjacent parts showing the use 70 of the modification shown in Figs. 5 and 6. 75

Reference is hereby made to the drawing, in which the central electrode stem 8 composed of any suitable substance is for the greater portion thereof inclosed by a thick sleeve 9 of insulating material which is 80 preferably the substance now on the market called "Isolit." To secure the said insulating-sleeve 9, I construct the same with the annular enlargement 10, which is shaped to engage within an annular recess formed in 85 the outer or grounded electrode-shell 11, said recess terminating at the bottom thereof in a seat which engages with the base of said enlargement and firmly holds the same in proper relation. The collar 12, is threaded 90 to engage with the inner surface of the shell electrode, and to be turned down upon the top of said enlargement as shown, a small air space, however, being left between the inner surface of said collar and the outer 95 surface of the insulation. At the base of said insulating-sleeve and integral therewith is the downwardly projecting flange 13, which is shaped to leave a considerable 100 space between the same and the grounded electrode, and is formed to have the recess 14, the top of which is shaped to receive and hold the head 15 at the lower end of the electrode stem 8 and prevent its upward movement. To the head 15 is affixed in any 10 suitable manner the shank of the sparking terminal 16, the upper half of which shank is indorsed by the flange 13 having considerable space between the two. The lower part 11 of said shank bearing the terminal point

is in the center of the large recess formed by the unfilled lower portion of the grounded electrode shell 11, except that the said point 17 is turned near its extremity to be 5 in close proximity to the sparking edge of said grounded electrode. As a further protection to the upper extremity of said insulating-sleeve 9 and as a means for conveniently handling the spark-plug when heated, 10 I mount the cap 18, formed of wood fiber or other material which is both a good insulator and a poor conductor of heat, upon the upper part of the stem 8, the edges of said cap extending downwardly to protect the 15 exposed portion of the insulation and being separated therefrom by a narrow air space, which serves to cool the cap and prevent its becoming heated. Above the cap 18, upon the screw threaded end of said stem 8 are 20 also mounted the washer 19, the binding nut 20 and the thumb screw 21 for the purpose of affording a binding post for electrical connection to the wire from the generator.

All of the above description applies to the 25 spark-plug as a whole, which is complete in itself and is designed to be readily removed from the combustion chamber or installed therein without disturbing the relation of the electrodes. For the purpose of 30 attaching the said spark plug to the combustion chamber, I employ a holder 22 which is formed with a screw threaded base for the purpose of engaging with a screw threaded orifice in said chamber (not shown) and to 35 be firmly secured therein, such engagement being effected by means of a wrench applied to the polygonal surface 23 formed on the exterior of said holder. The interior of said holder is made hollow for the purpose of 40 permitting the insertion of the spark-plug, so that the ends of the electrodes shall be in proper position in the combustion chamber. For the purpose of securing the said plug, I form the exterior of said plug with 45 an annular projection 24 and an annular recess 25 immediately above the same, said projection 24 engaging with the lower part of the inclined seat 26. Above the said projection and in contact with the upper part of 50 said inclined seat I locate the open ring 27 composed of metal of such resilience as to cause the same to seek the top of said inclined seat when not acted upon by the lower end of the locking nut 28, which nut is threaded to 55 engage with the recess in said holder at the upper part thereof. (See Fig. 3.) To insert the spark plug within said holder, the ring 27 is first placed within the same upon the top of the inclined seat 26; the lock nut 28 is then placed in proper position and turned down until the lower end of said nut is nearly in contact with said ring. The 60 plug may then be inserted without difficulty through the nut and ring and the projection 65 24 caused to rest upon the inclined seat 26.

Upon again turning the lock-nut 28, the end of the same comes into contact with said ring and forces it downwardly against said projection 24 and into the recess 25, where the said ring 27 rests equally upon said projection and inclined seat, the diameter of said ring being made great enough for this purpose. When in such position the ring securely holds the spark plug within its holder, and it is only by loosening the locking nut 28 and permitting the ring to ascend to the top of the inclined seat that the plug can be removed from said holder. 70 75

In Figs. 5, 6 and 7, I have shown a modification of the resilient spring holding means, in that I have employed for this purpose the lower end of the locking nut 28, the said end being extended somewhat lower and being split into the resilient arms 29, the extremity of each of which is shaped 80 to engage with both the said projection and inclined seat as shown in Fig. 7, and to securely lock the said plug to the holder. 85

One important improvement covered by my invention is the new arrangement of 90 parts permitting the spark-plug to be turned completely around in its holder or to any part of the circumference of the same without removing the plug from the holder. To accomplish said result it is only necessary 95 to partially loosen the locking-nut 28, when the ring will retreat sufficiently from its engagement with the projection 24, to permit the plug to be turned as described. So far as I am aware no prior device discloses this 100 feature, and I desire to cover this improvement in the broadest manner possible, though I do not desire to limit my broad invention to include merely this feature in combination with other parts of my improved construction. Neither do I desire to limit my 105 invention to other exact and specific parts, it being obvious that modification and changes could be effected in my device without departing from the spirit of my invention. 110

What I claim and desire to secure by Letters Patent is,—

1. In a spark plug, a metallic shell electrode, a projection upon the exterior of said electrode, a hollow metallic holder shaped to receive and hold said electrode and the projection thereon, combined with a lock nut and a metallic spring coöperating therewith and engaging with said projection and locking the same within said holder. 115 120

2. In a spark plug, a metallic shell electrode, an annular projection upon said electrode, a hollow metallic holder shaped to receive said electrode and having an annular recess therein, the bottom of said recess terminating in an inclined seat shaped to engage said projection, combined with a lock nut and a metallic packing coöperating therewith and engaging with both said seat 125 130

and projection and locking the same together.

3. In a spark plug, a metallic shell electrode, an annular projection upon said holder, 5 a hollow metallic holder shaped to receive said electrode and having therein an annular recess, the bottom of said recess terminating in an inclined seat shaped to engage said projection, a metallic packing ring engaging with 10 both said seat and projection, and a locking nut threaded to engage said recess and to engage with said ring and lock the same against said seat and projection.

4. In a spark plug, a metallic shell electrode, an annular projection upon said 15

holder, a hollow metallic holder shaped to receive said electrode and having therein an annular recess, the bottom of said recess terminating in an inclined seat shaped to engage said projection, a resilient metal ring 20 engaging with both said seat and projection, and a nut threaded to engage said recess and to engage with said means and lock the same against said seat and projection.

In testimony whereof I have affixed my 25
signature, in presence of two witnesses.

WRAY FALWELL.
